UNITED STATES PATENT OFFICE.

CHARLES B. McALVAY, OF JACKSON, MICHIGAN, ASSIGNOR OF THREE-EIGHTHES TO CHARLES H. CHRISTOPHER, OF SAME PLACE.

LUBRICATOR.

SPECIFICATION forming part of Letters Patent No. 294,399, dated March 4, 1884.

Application filed December 14, 1883. (No model.)

To all whom it may concern:

Be it known that I, CHARLES B. McALVAY, a citizen of the United States of America, residing at Jackson, in the county of Jackson 5 and State of Michigan, have invented certain new and useful Improvements in Lubricators for Steam-Engines, of which the following is a specification, reference being had therein to the accompanying drawings.

10 This invention pertains to improvements in lubricators for steam-engines, having for its object to effect the proper feeding of the lubricant and the consequent proper lubrication of the parts; and it consists of the combination 15 and arrangement of parts, substantially as hereinafter fully set forth and claimed.

In the accompanying drawings, Figure 1 is 20 a sectional elevation of my lubricator, and Fig. 2 is a front elevation of the same. Fig. 25 3 is a detail of casting B, showing the registering mechanism and sight-feed.

In carrying out my invention I employ a reservoir, A, preferably cylindric in form, to contain the oil or other lubricant, to the bottom end of which is applied a "petcock," a, to permit the drawing off of the water of condensation accumulating in the cylinder or reservoir. The reservoir or cylinder is filled 30 with lubricant through an opening fitted with a screw-plug, a'.

B is a casting screwed into the top end of the cylinder A, and provided with the double-apertured plug B', and with two passages, C C', one extending through it from end to end, except where interrupted by the plug, while the other passage, which is also interrupted by the said plug, (the apertures of the latter being arranged coincidently with the passages C C,) is caused to connect or communicate 40 with a shallow chamber, D, in the upper part of the casting B. This chamber D has in its rear side a mirror or reflector, D', while a plate of glass or transparent material, D², is set in its front open side, and held in position (it 45 may be) by a frame, D³, secured thereon by screws passing through said frame and into the casting. The upper end of the casting is screw-threaded, to effect the connection thereof to a pipe leading to the engine and in com-

munication with a globe-valve. (Not shown.) 50 The upper end of the passage C is "needle-pointed," said needle-point projecting slightly into the chamber D, as at b; while from the upper side of the chamber D extends through the casting a duct or passage, F, which, as 55 well as the passage or duct C, communicates with the pipe leading to the globe-valve and engine above referred to.

Communicating with the lower end of the passage or duct C is a narrow pipe or duct, F', leading down into the lubricant reservoir or cylinder A, with its lower end terminating contiguously to the bottom of the said reservoir and to the waste or pet cock a.

In operation, the reservoir A being filled 65 with the required lubricant, the globe-valve is opened, (the plug or valve B' remaining as yet closed,) when the steam will rush into and fill the passage-ways and chamber in the casting B, and, as soon as said steam condenses, the plug B' will be opened, establishing communication with the reservoir and allowing the condensed steam or water of condensation to flow into the latter, whence that from duct C' will pass through the pipe F' 70 into the reservoir, and that from duct C will flow directly into the reservoir, and sinking by gravity below the lubricant, (a portion thereof remaining or rising into and thereby sealing the lower end of pipe F' against the 75 entrance of lubricant therein,) the lubricant will be forced up through the duct or passage C. From this passage it will be seen to enter the chamber D, "drop by drop," through the glass or transparent front of said chamber. 80 The quantity of the lubricant fed to the parts to be lubricated is regulated, and to this end is registered by connecting with plug B' the pointer G and scale of graduation G'.

Having thus fully described my invention, 90 I claim and desire to secure by Letters Patent—

1. In a lubricator, the combination of the reservoir A, having screw-plug a', petcock a, casting B, having screw-threaded upper end 95 and apertures C and C', double-apertured plug B', chamber D, having duct or passage F and mirror D', glass D², secured in frame D³, and

pipe or duct F', substantially as shown, and for the purpose described.

2. A lubricator consisting of a reservoir, A, having opening therein a petcock, a, and screw-plug a', casting B, having ducts C and C', plug B', registering mechanism, and a screw-threaded upper end chamber, D, having duct or passage F, mirror D', glass D', and pipe or

duct F', substantially as shown, and for the purpose described.

In testimony whereof I affix my signature in presence of two witnesses.

CHARLES B. McALVAY.
